Des 577

James Cowles, of Rochester, N.Y.

Assignor to

Albert G. Bristol, of Rochester aforesaid,

Letters Patent No. 577 Dated June 28th 1853,

numm

The schedule referred to in these Letters Patent and matting part of the same

nummum

To all whom it may concern:

Be it known that I, James Cowles, of the City of Rochester, in the County of Monroe, and State of New York, have invented a new and original design for a Register face and I do hereby declare that the following is a full and exact description of the same,

My invention consists in the arrangement of certain open work, to be cast in iron or other metal as shown in the accompanying drawing —

The white curved lines show the metal bars and the shaded portions the openings or interstices for the passage of air. The whole together forming a new design —

What I claim as my invention and desire to secure by

U.S. 577

2

letters patent is the new & original design for a Register face formed by the peculiar arrangement of the metallic bars as shown in the accompanying drawing.
